(57) **ABSTRACT**

Systems and methods for performing surgery are provided, which permit multiple tool tips to be interchanged within an instrument shaft during a minimally invasive procedure. The surgical device holds a plurality of interchangeable tool tips such that a selected tool tip from a chamber of a magazine can be mounted at the distal end of an elongated shaft for a laparoscopic surgery. In this manner, multiple tool types can be interchanged within a shaft without having to remove the instrument from the patient for tool changes, thereby increasing surgical efficiencies and reducing the number of tools needed for a procedure.

**SURGICAL SYSTEM HAVING
INTERCHANGEABLE TOOL TIPS AND
METHODS OF USE THEREOF**

**CROSS-REFERENCE TO RELATED
APPLICATIONS**

This application is a continuation-in-part application of PCT/EP2025/050952, filed Jan. 15, 2025, which claims priority to European Patent Appl. No. 24167051.2, filed Mar. 27, 2024, and European Patent Appl. No. 24151941.2, filed Jan. 15, 2024, the entire contents of each of which are incorporated herein by reference.

TECHNICAL FIELD

This technology generally relates to devices for performing surgery, such as microinvasive surgical devices having interchangeable tool tips.

BACKGROUND

During a surgical procedure, e.g., laparoscopy, if a different tool tip is to be used, the handheld surgical device inserted within a patient must be removed and a different handheld surgical device having the desired tool tip must be introduced through the incision into the patient's body, resulting in a prolonged time in operation in which the patient may be under anesthesia. In laparoscopic surgeries, a number of different tools are used, which have to be switched an average of 20 to 50 times during the procedure. This can result in distracting workflows for surgeons and a loss of valuable surgical time.

WO 2002/065933 discloses a remotely controllable surgical instrument comprising an instrument shaft having a proximal end drivably intercoupled to a drive unit and a distal end insertable within a subject for performing a medical procedure at an operative site within the subject, a remotely disposed user interface interconnected to a remotely disposed signal processor which processes commands received from the user interface, the signal processor interconnected to the drive unit for transmitting processed command signals received from the user interface to the drive unit characterized in that the instrument shaft comprises an elongated disposable shaft removably interconnected to the drive unit via a coupling mechanism and a distal instrument drivable via cables.

U.S. 2007/0239186 discloses a method of performing a medical procedure (e.g., a cardiac bypass procedure) on a patient. The method comprises introducing at least one medical instrument into a patient (e.g., percutaneously), conveying control signals from a remote controller to a drive unit, and operating the drive unit in accordance with the control signals to actuate at least one tool respectively located on the medical instrument(s) to transversely secure a first anatomical vessel (e.g., a blood vessel) to a sidewall of a second anatomical vessel (e.g., another blood vessel). In one method, the control signals are conveyed from the remote controller to the drive unit in response to user commands. The user commands may be movements made at a user interface that correspond to movements of the medical instrument(s).

While the prior art approaches may be satisfactory in some regards, they have certain shortcomings and disadvantages.

2

In view of the foregoing drawbacks of previously known systems and methods, there exists a need for an improved surgical devices and method for use thereof.

For example, there exists a need for surgical devices that allow for improved efficiency of surgery and methods for use of the devices.

Additionally, there exists a need for surgical devices that enable more flexible usage of operating tools and method for using the devices.

SUMMARY

Provided herein are improved systems and methods for performing microinvasive surgery. In accordance with one aspect, a surgical device is provided. The surgical device may comprise a body portion, an elongated shaft having a proximal end coupled to the body portion, a distal end, and a lumen extending therebetween, and a magazine coupled to the body portion and comprising a plurality of chambers, each chamber configured to receive an interchangeable tool tip therein. The magazine may be configured to be selectively actuated to align a selected chamber of the plurality of chambers with the proximal end of the elongated shaft. The surgical device further may comprise a tool activation mechanism comprising a distal region configured to be releasably coupled to the interchangeable tool tip of the selected chamber. The tool activation mechanism may be configured to transition between a retracted configuration within the body portion where the distal region is disposed proximal to the selected chamber, and an extended configuration where the distal region is coupled to the interchangeable tool tip of the selected chamber and extends through the lumen of the elongated shaft such that the interchangeable tool tip is mounted at the distal end of the elongated shaft.

The tool activation mechanism may be substantially rigid against compression and elongation and flexible against bending as the tool activation mechanism transitions from the extended configuration to the retracted configuration. For example, the tool activation mechanism may comprise a rack, and an actuation rod disposed within a lumen of the rack. The rack and the actuation rod may be configured to move together as the tool activation mechanism transitions between the retracted configuration and the extended configuration. In some embodiments, the rack may comprise a plurality of joint-connected rack elements. Moreover, the rack may be configured to substantially bend about a single bend axis. A distal end of the rack may be configured to releasably engage a proximal portion of the interchangeable tool tip, and a distal end of the actuation rod may comprise a coupling element configured to be releasably coupled to an engagement portion of the interchangeable tool tip. In addition, when the coupling element is coupled to the engagement portion, the actuation rod may be configured to be actuated to move axially relative to the rack to thereby actuate the interchangeable tool tip. For example, the interchangeable tool tip may comprise a tool configured to be actuated in an open and close degree of freedom, such that actuation of the actuation rod may actuate the interchangeable tool tip in the open and close degree of freedom.

In addition, the body portion may comprise an actuation bar configured to be releasably coupled to a proximal coupling element of the actuation rod in the extended configuration. The actuation bar may be configured to be actuated to move the actuation rod axially relative to the rack. Further, the body portion may be sized and shaped to be held in a user's palm, and the body portion may comprise an interface operatively coupled to the actuation bar, the

interface configured to be actuated by the user to actuate the actuation bar and move the actuation rod axially relative to the rack. Moreover, the rack may comprise a geared outer surface, and the body portion may further comprise a worm gear operatively coupled to a pinion gear operatively coupled to the geared outer surface, the worm gear configured to be actuated to cause rotation of the pinion gear to thereby cause translational movement of the rack via a geared connection between the pinion gear and the geared outer surface.

Each chamber of the plurality of chambers of the magazine may be sized and shaped to prevent proximal movement of the interchangeable tool tip beyond a proximal end of the chamber. Moreover, one or more chambers of the plurality of chambers of the magazine may comprise a geometry configured to receive the interchangeable tool tip in a predetermined aligned manner. For example, the geometry may be configured to prevent rotation of the interchangeable tool tip relative to the chamber. In addition, the body portion may comprise a receptacle sized and shaped to slidably receive the tool activation mechanism in the retracted configuration. For example, the receptacle may be configured to permit the tool activation mechanism to substantially bend about a bend axis as the tool activation mechanism transitions from the extended configuration to the retracted configuration. The bend axis may be substantially orthogonal to a longitudinal axis of the elongated shaft. In some embodiments, the elongated shaft may be configured to transmit electric power from a generator to the interchangeable tool tip mounted at the distal end of the elongated shaft. Accordingly, the interchangeable tool tip may comprise a tool configured for electric cauterization.

The surgical device further may comprise one or more motors operatively coupled to the magazine, the one or more motors configured to be actuated to move the magazine relative to the body portion. Moreover, the surgical device may comprise a user interface operatively coupled to the one or more motors, the user interface configured to receive user input indicative of the selected chamber. Accordingly, the one or more motors may be configured to actuate the magazine to align the selected chamber with the proximal end of the elongated shaft based on the user input. Additionally, the surgical device may comprise an actuator configured to rotate the elongated shaft and the interchangeable tool tip mounted thereon relative to the body portion. The distal end of the elongated shaft may be configured to prevent rotation of the interchangeable tool tip relative to the elongated shaft. For example, the actuator may comprise a rotatable knob disposed on the body portion.

Moreover, the surgical device may comprise a handle at the proximal end of the elongated shaft, the handle configured to be held by the user for performing surgery. In some embodiments, the surgical device may be configured for use with a surgical robot system. Additionally, the surgical device may be configured to be operatively coupled to a display that displays various types of interchangeable tool tips within the plurality of chambers, such that a user may be permitted to select a type of interchangeable tool tip using the display. The interchangeable tool tips within the plurality of chambers may comprise at least one of a hook, a grasper, or scissors. In some embodiments, the magazine may be rotatably coupled to the body portion, and the plurality of chambers may be equally radially disposed about a longitudinal axis of the magazine.

BRIEF DESCRIPTION OF THE DRAWINGS

FIG. 1 illustrates an exemplary system for performing microinvasive surgery in accordance with some embodiments.

FIG. 2A illustrates an exemplary surgical device of the system of FIG. 1, and FIG. 2B is an exploded view of the surgical device of FIG. 2A.

FIG. 2C illustrates exemplary components of a rack drive and a magazine drive of an exemplary surgical device.

FIG. 3A illustrates an exemplary body portion of the surgical device of FIGS. 2A and 2B constructed in accordance with some embodiments.

FIG. 3B illustrates an alternative exemplary body portion of the surgical device constructed in accordance with some embodiments.

FIG. 4A illustrates an exemplary tool activation mechanism comprising a rack and rod in accordance with some embodiments.

FIG. 4B illustrates the distal portion of the exemplary rod of the tool activation mechanism of FIG. 4A, and FIG. 4C illustrates the proximal portion of the exemplary rod of the tool activation mechanism of FIG. 4A.

FIG. 4D illustrates the proximal portion of an alternative exemplary rod constructed in accordance with some embodiments.

FIG. 4E illustrates the distal portion of the exemplary rack of the tool activation mechanism of FIG. 4A.

FIG. 4F illustrates the distal portion of an alternative exemplary rack constructed in accordance with some embodiments.

FIGS. 5A to 5D illustrate an exemplary rack constructed in accordance with some embodiments.

FIGS. 6A to 6D illustrates an alternative exemplary rack comprising an inner metal portion and an outer polymer layer in accordance with some embodiments.

FIGS. 7A to 7D illustrates another alternative exemplary rack comprising a plurality of joint-connected rack elements in accordance with some embodiments.

FIG. 8 illustrates the distal end of the surgical device and various interchangeable tool tips.

FIGS. 9A to 9F illustrate an exemplary magazine of the surgical device constructed in accordance with some embodiments.

FIGS. 10A to 10C illustrate advancement of a select tool tip from the magazine of the surgical device.

FIGS. 11A and 11B illustrate actuation of the tool activation mechanism of the surgical device in accordance with some embodiments, and FIGS. 11C and 11D illustrate a tool change.

FIGS. 12A to 12G illustrate the coupling mechanism between the tool activation mechanism and an actuation bar of the surgical device during operation of the surgical device.

FIG. 13 illustrates a grasper tool tip mounted at the distal region of an alternative exemplary surgical device configured to transmit electrical energy in accordance with some embodiments.

FIG. 14 illustrates the distal region of another alternative exemplary surgical device configured to transmit electrical energy constructed in accordance with some embodiments.

FIG. 15A illustrates an exemplary tool tip configured for tripolar electric cauterization constructed in accordance with some embodiments, and FIG. 15B illustrates the tool tip of FIG. 15A mounted at the distal region of the surgical device of FIG. 14.

FIG. 16 illustrates the proximal region of an alternative exemplary tool tip configured for tripolar electric cauterization constructed in accordance with some embodiments.

FIG. 17 illustrates an exemplary system for performing microinvasive surgery having a power generator operatively

coupled to the surgical device via a switching module in accordance with some embodiments.

FIG. 18 illustrates exemplary electrode assignment options for various exemplary interchangeable tool tips in accordance with some embodiments.

FIG. 19 illustrates additional exemplary interchangeable tool tips constructed in accordance with some embodiments.

DETAILED DESCRIPTION

Embodiments of this technology are directed to exemplary systems and methods for performing surgical procedures, particularly via a surgical device configured to change tool tips while the operating end of the surgical device remains within the patient's body. As used herein, the term "distal" may refer to a side of the surgical device facing a patient, e.g., when a tool tip mounted to the surgical device and/or the elongated shaft of the surgical device is inserted into a body of the patient, and/or a direction towards this side. The term "proximal" may refer to a side of the surgical device opposite to a side facing the patient and/or to a corresponding direction.

Referring now to FIG. 1, an exemplary system for performing surgery is provided. System 10 may include surgical device 100 configured for performing surgical procedures, controller 12 operatively coupled to surgical device 100, and user interface 14 having a display configured to display a plurality of interchangeable tool tips to facilitate selection of a desired tool tip for use with surgical device 100 by a user. Controller 12 may be operatively coupled to a power generator for providing electrosurgical power to surgical device 100 to operate surgical device 100 and/or the selected tool tip mounted thereto, e.g., when the selected tool tip is configured for electric cauterization, as described in further detail below.

Referring now to FIGS. 2A to 2C, an exemplary surgical device for performing microinvasive surgical procedures including, for example, laparoscopy, is provided. Surgical device 100 may be a handheld surgical device configured for introducing a selected tool tip, e.g., tool tip 160 configured for microinvasive surgery, into a body, e.g., of a human, or in another example, into a body of an animal. One or more of the interchangeable tool tips may be configured for different surgical tasks, such as cutting, grasping, hooking, or electric cauterization, as described in further detail below with regard to FIG. 13, etc. Surgical device 100 may include body portion 110, which may be sized and shaped to be held in a user's palm and/or integrated into a surgical robot system, elongated shaft 102 having a proximal end coupled to body portion 110, distal end 106, and a lumen extending therebetween forming an internal channel, and magazine 170 comprising a plurality of chambers, e.g., tool receiving locations, each chamber sized and shaped to removably receive an interchangeable tool tip, e.g., tool tip 160, therein. Accordingly, magazine 170 may be configured to hold multiple interchangeable tool tips simultaneously. Magazine 170 may be selectively actuated to align a desired chamber with the lumen of elongated shaft 102, such that a desired tool tip within the desired chamber may be advanced from magazine 170, e.g., via tool activation mechanism 103, and interchangeably mounted to distal end 106 of elongated shaft 102, e.g., in a mounted configuration, as described in further detail below. Accordingly, elongated shaft 102, particularly distal end 106 of elongated shaft 102, may be configured for insertion into the patient's body, allowing distal end 106 to reach a point of surgery remote from an incision through which the tool is introduced.

Unlike other commercially available handheld surgical devices where, if a different tool tip is to be used, the handheld surgical device inserted within a patient must be removed and a different handheld surgical device having the desired tool tip must be introduced through the incision into the patient's body, resulting in a prolonged time in operation in which the patient may be under anesthesia, handheld surgical device 100 may be configured to change the tool tip mounted at distal end 106 of elongated shaft 102 while distal end 106 is located inside the patient's body, e.g., in a surgery configuration, without removing and reinserting the surgical device into the patient's body.

As shown in FIG. 2B, an exploded view of surgical device 100, surgical device 100 may include tool activation mechanism 103 slidably disposed therein and transitional between a retracted configuration within body portion 110, e.g., within receptacle 108 of body portion 110, and an extended configuration to thereby mount the selected tool tip 160 to distal end 106 of elongated shaft 102. For example, in the retracted configuration, at least the proximal portion of tool activation mechanism 103 may be in a rolled configuration within receptacle 108, such that the distal end of tool activation mechanism 103 is disposed proximal to magazine 170, e.g., proximal to the select chamber of magazine 170 that is aligned with the lumen of elongated shaft 102. Accordingly, receptacle 108 may be configured to store rack 120 in a spirally or circularly bent shape. Moreover, surgical device 100 may include a track sized and shaped to slidably receive tool activation mechanism 103 therein, the track including the lumen of elongated shaft 102 and extending through receptacle 108 such that tool activation mechanism 103 may move between the retracted configuration within receptacle 108 and the extended configuration within the lumen of elongated shaft 102.

Thus, tool activation mechanism 103 may be configured to bend about a bend axis, e.g., the central axis of receptacle 108 orthogonal to the longitudinal axis of the track of surgical device 100, as tool activation mechanism 103 transitions to the retracted configuration. The bend axis and the longitudinal axis of track 101 within body portion 100 may be spaced apart from each other, e.g., by a distance substantially identical to a bending radius of the proximal section of tool activation mechanism 103 received in receptacle 108. In other words, a longitudinal axis of track 101 may be substantially identical to a tangent of tool activation mechanism 103 when rolled in receptacle 108. Advantageously, bending of tool activation mechanism 103 may be reduced, e.g., compared to receptacles comprising a bending axis that intersect with the longitudinal axis of track 101. When transitioning from the retracted configuration to the extended configuration, the distal end of tool activation mechanism 103 may engage with the tool tip disposed within the chamber of magazine 170 that is aligned with the track of surgical device 100, and advance the tool tip from magazine 170 and through the lumen of elongated shaft 102 for mounting at distal end 106 of elongated shaft 102. Accordingly, tool activation mechanism 103 may be configured to transfer tension and compression forces to tool tip 160.

As shown in FIG. 2C, surgical device 100 may include rack drive 121 disposed on body portion 110, and configured to be actuated to move tool activation mechanism 103 between the retracted and extended positions. Rack drive 121 may comprise a rack-drive-motor and a rack-drive transmission. For example, rack drive 121 may include one or more motors, e.g., motor 107a, operatively coupled to worm drive 109 having pinion gear 111, which may be

operatively coupled to tool activation mechanism 103, e.g., via a geared connection, such that actuation of motor 107a causes worm drive 109 to rotate pinion gear 111, which causes translational movement of tool activation mechanism 103, as described in further detail below. Rack drive 121 may be self-locking, e.g., not back-drivable. In other words, if the rack-drive-motor does not apply a torque to a motor-side of the rack-drive-transmission, a force applied to rack 120 may not result in a movement of the rack-drive-transmission, e.g., rack drive 121 inhibits movement of rack 120 apart from deformation of rack 120 due to external forces. Accordingly, tool tip 160 may be held in a safe manner when mounted to distal end 106 of elongated shaft 102, providing for reliable mounting of the tool tip. In addition, worm drive 109 may comprise a self-locking worm-gear unit, thereby allowing for a compact and simple solution without requiring additional parts for locking rack drive 121. Accordingly, rack drive 121 may remain locked in case of an interruption of electrical power, thus providing for a defined position of tool 160 and increased safety in case of an electrical fault. Additionally, or alternatively, the rack-drive-transmission may comprise an automatic locking mechanism. For example, the rack-drive-transmission may comprise a pin for locking the transmission when motor 107a does not drive rack 120. In some embodiments, motor 107a may apply a holding torque, e.g., by means of a position control activated once tool tip 160 is mounted to distal end 106 of elongated shaft 102.

Moreover, surgical device 100 may comprise a magazine drive configured to be actuated to selectively rotate magazine 170 to a select angular position relative to body portion 110, to thereby align the select chamber of magazine 170 with the track of surgical device 100, and accordingly, the lumen of elongated shaft 102, as described above. The magazine drive may comprise, for example, a stepper motor, and/or a BLDC-motor with a position sensor, such as a hall sensor, and an appropriate position control, such as a PID-control, as well as a gear stage, such as a planetary gear. For example, as shown in FIG. 2C, the magazine drive may include one or more motors, e.g., motor 107b, operatively coupled to a switchable gear, e.g., drive gear 115, which may be operatively coupled to driven gear 173 of magazine 170, e.g., via a geared connection to connect motor 107b and magazine 170, such that actuation of motor 107b causes rotation of drive gear 115, which causes rotation of driven gear 173, and accordingly, magazine 170 relative to body portion 110.

In addition, the magazine drive may comprise one or more sensors configured for sensing a position of magazine 170, such as an angular position and/or a translational position of magazine 170. For example, in case of the rotatable magazine 170, the sensor may be configured for sensing the angular position of magazine 170, and in case of magazine 170 configured to be moved along the translation axis, the sensor may be configured for sensing a translational position of magazine 170. The one or more sensors configured for sensing the position of magazine 170 may comprise at least one of an incremental encoder or a reference sensor, such as reference switch, e.g., a proximity sensor. Alternatively, the one or more sensors may comprise an absolute encoder. Alternatively, in some embodiments, the one or more sensors may comprise a simple switch configured to be triggered every time the angular position of magazine 170 is such that a chamber of magazine 170 is aligned with the track of surgical device 100.

As shown in FIG. 2C, the proximal end of elongated shaft 102 may be coupled to body portion 110, and may comprise

actuator 104, e.g., an orientating formation, configured to, upon actuation, rotate elongated shaft 102, and accordingly tool tip 160 mounted to distal end 106 of elongated shaft 102, about its longitudinal axis relative to body portion 110. For example, actuator 104 may be a knob fixedly coupled to elongated shaft 102, and rotatably coupled to body portion 110, such that a user may actuate actuator 104 by rotating actuator 104 relative to body portion 110.

FIG. 3A illustrates body portion 110, with magazine 170, drive rack 121, and receptacle 108 omitted for clarity. As shown in FIG. 3A, body portion 110 may include handle portion 112 sized and shaped to be held by a user's palm, and a connection cable configured to electrically couple surgical device 100 to a control unit, e.g., controller 12, as shown in FIG. 1, to thereby provide electrical power to surgical device 100. As shown in FIG. 3A, body portion 110 may include frame 116 sized and shaped to rotatably receive magazine 170 therein, and disposed proximal to elongated shaft 102, such that magazine 170 is in communication with the proximal portion of elongated shaft 102. In addition, the track of surgical device 100, e.g., track 101, may extend through body portion 110, such that the longitudinal axis of track 101 may be aligned with the longitudinal axis of the selected chamber of magazine 170.

Moreover, body portion 110 may include one or more actuators configured to be actuated by the user to control one or more functions of surgical device 100. For example, body portion 110 may include actuator 113a, which may be actuated to apply electrical energy to the select tool tip, e.g., when tool tip 160 comprises an electrical tool tip, as described in further detail below. In some embodiments, actuator 113a may comprise two distinct actuators, for example, a first actuator configured to be actuated to apply electrical energy with normal frequency, e.g., to coagulate tissue with normally bipolar energy via a bipolar grasper tool tip, and a second actuator configured to be actuated to apply electrical energy with high frequency, e.g., to cut through tissue with normally monopolar energy via a monopolar L-hook tool tip.

In addition, body portion 110 may include actuator 113b, which may be actuated to select the desired tool tip from a plurality of available tool tips. For example, the plurality of available tool tips may be displayed via display 14, such that actuation of actuator 113b permits the user to select the desired tool tip displayed on display 14. Body portion 110 further may include safety actuator 113c, which may be required to be actuated, e.g., continuously pressed, during the tool selection process to avoid accidental tool selection. For example, actuator 113c may be required to be actuated in order to permit actuation of actuator 113b. As shown in FIG. 3A, body portion 110 further may include actuator 114, e.g., an operating lever, configured to be manually actuated by the user to actuate tool activation mechanism 103 to thereby actuate the tool tip mounted at distal end 106 of elongated shaft 102. For example, actuator 114 may be operatively coupled to actuation bar end piece 118, which may be configured to releasably engage tool activation mechanism 103 when the select tool tip is mounted at distal end 106 of elongated shaft 102 via tool activation mechanism 103, such that actuation of actuator 114 causes actuation of tool activation mechanism 103, as described in further detail below. For example, actuation bar end piece 118 may be configured to releasably engage the proximal coupling element of the rod of tool activation mechanism 103, e.g., coupling element 132 of rod 130, as described in further detail below with regard to FIG. 4C.

As described in further detail below with regard to FIG. 4D, the coupling element of the rod of the tool activation mechanism may comprise different shaped profiles for releasable engagement with the actuation bar end piece of the body portion of the surgical device. Accordingly, the actuation bar end piece may have a corresponding geometry for releasably engaging with the coupling element of the rod, as shown in FIG. 3B. Body portion 110' may be constructed similar to body portion 110. For example, track 101', handle portion 112', actuators 113a'-113c', operative lever 114', and frame 116' correspond with track 101, handle portion 112, actuators 113a-113c, operative lever 114, and frame 116 of body portion 110. Body portion 110' differs from body portion 110 in that actuation bar end piece 118' comprises a geometry configured to releasably engage with coupling element 132' of rod 130', as described in further detail below with regard to FIG. 4D.

Alternatively, in some embodiments, surgical device 100 may be configured to be robotically operated, e.g., via a linear drive and/or an excentre, for robot-assisted surgery, as described in EP 24167051, the entire contents of which is incorporated herein by reference.

Referring now to FIG. 4A, an exemplary tool activation mechanism 103 is provided. As shown in FIG. 4A, tool activation mechanism 103 may comprise rack 120 having proximal end 122, distal end 124 configured to releasably engage with a proximal end of tool tip 160, and a lumen extending therebetween, the lumen sized and shaped to slidably receive rod 130 therein. Rack 120 is configured to move the select tool tip from the chamber of magazine 170 that is aligned with track 101 of surgical device 100 along the longitudinal axis of elongated shaft 102 to distal end 106 of elongated shaft 102, as well as from distal end 106 back to the chamber of magazine 170. Accordingly, rack 120 is configured to transmit compressive forces to tool tip 160. Rack 120 may be configured such that rack 120 is substantially rigid against compression. For example, in an unbiased configuration of rack 120, adjacent windings of the metal wire may be in contact with each other, thus providing for an increased stiffness against compression of rack 120.

In some embodiments, rack 120 may comprise a stiffness against compression of, e.g., at least 300 N/mm, at least 600 N/mm, or at least 1000 N/mm. Moreover, rack 120 may be configured such that rack 120 is flexible against bending, e.g., rack 120 may have a sufficiently low stiffness against bending such that it may be bendable about the bend axis of receptacle 108. In other words, rack 120 may be configured for transmitting compressive forces and may tolerate being bent about at least one bend axis. Preferably, rack 120 may only bend about a single bend axis. For example, in some embodiments, rack 120 may comprise a stiffness against bending of at most 600 N/mm², at most 500 N/mm², or preferably at most 470 N/mm². Thus, rolled storage of rack 120 and rod 130 within receptacle 108 is enabled, e.g. storage with a bending radius of at most 60 mm, at most 50 mm, or at most 40 mm. In some embodiments, the track extending through receptacle 108 may comprise a spiral configuration such that in the retracted configuration, tool activation mechanism 103 may be spirally wounded within receptacle 108. Accordingly, when spirally wounded, rack 120 may only substantially bend about a single bend axis as the spiraling configuration is not aligned in a single plane.

Rod 130 may be configured to transmit tensile and compressive forces to tool tip 160, to thereby mechanically actuate a multi-part tool tip 160, as described in further detail below. As shown in FIG. 4A, the proximal end of rod 130 may comprise a proximal coupling element 132 con-

figured to releasably engage with actuation bar end piece 118, and distal coupling element 134 configured to be releasably coupled to a base of tool tip 160. Rod 130 may be substantially rigid in tension and compression, and flexible against bending. For example, rod 130 may be a push-pull cable, a metal rod, e.g., a steel cable comprising a steel filament. In some embodiments, rod 130 may be formed by a plurality of pieces operatively coupled together.

As shown in FIG. 4B, distal coupling element 134 may comprise a claw, e.g., one or more fingers 135, configured to releasably engage the base of tool tip 160. For example, fingers 135 may define a cavity sized and shaped to releasably receive the base of tool tip 160 therein. As shown in FIG. 4B, the cavity defined by fingers 135 may be open on its lateral sides to thereby permit the base of tool tip 160 to enter the cavity from the side, e.g., as magazine 170 is rotated relative to distal coupling element 134, as described in further detail below. For example, the cavity defined by fingers 135 may have a smaller width at its distal end compared with the middle and/or proximal portion of the cavity, the middle and/or proximal portion of the cavity having a geometry that corresponds with the base of tool tip 160. Alternatively, in some embodiments, distal coupling element 134 may be coupled to the base of tool tip 160 via, e.g., a magnetic connection. In some embodiments, e.g., when the selected tool tip is configured for electric cauterization as described in further detail below, distal coupling element 134 further may include sliding member 136. For example, sliding member 136 may be formed of a non-conductive material, and configured to facilitate transmission of one pole line for electrosurgical energy through the rod by isolating rod 130 and distal coupling element 134 from the inner wall of elongated shaft 102.

As shown in FIG. 4C, proximal coupling element 132 may be sized and shaped to facilitate a locking engagement between proximal coupling element 132 and actuation bar end piece 118. Moreover, proximal coupling element 132 may comprise a dome shaped section 133 configured to facilitate insertion into receptacle 108. Alternatively, in some embodiments, the proximal coupling element of the rod may comprise a rotationally symmetrical profile, e.g., symmetrical about a longitudinal axis of the rod, as shown in FIG. 4D. For example, rod 130' may be constructed similar to rod 130, except that proximal coupling element 132' having dome shaped section 133' of rod 130' comprises a rotationally symmetrical profile. Accordingly, proximal coupling element 132' of rod 130' may be configured to releasably engage with actuation bar end piece 118' of body portion 110' of FIG. 3B, as described above. As will be understood by a person having ordinary skill in the art, the proximal coupling element of the rod may have a configuration other than those illustrated in FIGS. 4C and 4D, and the actuation bar end piece of the body portion of the surgical device may have a corresponding geometry to releasably engage with the proximal coupling element. As shown in FIG. 4E, distal end 124 of rack 120 may comprise an enclosed profile. Alternatively, in some embodiments, the distal end of the rack may comprise a U-shaped or C-shaped profile, as shown in FIG. 4F. For example, rack 120' may be constructed similar to rack 120, except that distal end 124' of rack 120' comprises a U-shaped profile.

Referring now to FIGS. 5A to 5D, an exemplary body of rack 120 is provided. As shown in FIG. 5B, rack 120 may include lumen 123 extending therethrough and sized and shaped to slidably receive rod 130 therethrough. In addition, the lower surface of rack 120 may include track 125 sized and shaped to facilitate movement of rack 120 through track

101 of surgical device 100, e.g., when at least a portion of track 101 comprises a rail sized and shaped to slidably receive track 125. Moreover, rack 120 may be a gear rack. For example, as shown in FIGS. 5A, 5C, and 5D, the upper surface of the body of rack 120, e.g., the middle region of rack 120 between proximal end 122 and distal end 124, may comprise a linear gear section, e.g., geared surface 128 sized and shaped to be operatively coupled to pinion gear 111, e.g., via a geared connection, as described above. For example, geared surface 128 may comprise a plurality of teeth disposed along the upper surface of rack 120. Accordingly, actuation of worm gear 109 via motor 107a causes rotation of pinion gear 111, which causes translational movement of rack 120 via the geared connection between geared surface 128 and pinion gear 111. In addition, the lower portion of rack 120 opposite geared surface 128 may comprise a plurality of slits 126 configured to improve flexibility of rack 120 and facilitate bending of rack 120 about a bend axis, which may be orthogonal to the longitudinal axis of lumen 123 of rack 120. For example, upon bending of rack 120, the upper surface of rack 120 may form a concave shape, while the lower surface of rack 120 may form a convex shape, e.g., via opening of slits 126.

Referring now to FIGS. 6A to 6D, an alternative exemplary rack is provided. Rack 140 may be constructed similar to rack 120. For example, rack 140 may comprise lumen 143 sized and shaped to slidably receive rod 130 therethrough, track 145, geared upper surface 148, and plurality of slits 146, which correspond with lumen 123, track 125, geared upper surface 128, and plurality of slits 126 of rack 120. Rack 140 differs from rack 120 in that rack 140 may be formed of inner metal portion 147, e.g., a wound metal wire, such as a steel spring, and outer polymer layer 141, e.g., form of polypropylene. Accordingly, outer polymer layer 141 may define track 145, geared upper surface 148, and plurality of slits 146, and inner metal portion 147 may define lumen 145.

Referring now to FIGS. 7A to 7D, another alternative exemplary rack is provided. Articulated rack 150 may be constructed similar to rack 120. For example, articulated rack 150 may comprise lumen 153 sized and shaped to slidably receive rod 130 therethrough, track 155, and geared upper surface 158, which correspond with lumen 123, track 125, and geared upper surface 128 of rack 120. Articulated rack 150 differs from rack 120 in that instead of a plurality of slits disposed along the lower portion, articulated rack 150 may be formed of a plurality of rack elements 151 connected to one another via a plurality of joints or bolts, e.g., joints 156. Each rack element 151 may provide at least one rotational degree of freedom about the corresponding joint 156. Accordingly, articulated rack 150 may bend about its bend axis via plurality of joints 156. For example, plurality of rack elements 151 may be connected to one another via plurality of joints 156 in a manner such that articulated rack 150 may only bend about a single bend axis and only in a single direction.

Referring now to FIG. 8, exemplary tool tips are provided. As shown in FIG. 8, distal end 106 of elongated shaft 102 of surgical device 100 may comprise tool rotating structure 105 configured to mate with the select tool tip 160 in a manner such that tool tip 160 cannot rotate relative to elongated shaft 102 when tool tip 160 is mounted thereto, e.g., via a positive form-fitting connection. For example, tool rotating structure 105 may comprise a plurality of indentations disposed along an inner surface of elongated shaft 102 at distal end 106. Accordingly, as shown in FIG. 8, each tool tip, e.g., grasper tool tip 160a and hook tool tip

160b, includes proximal portion 164 having a corresponding geometry configured to mate with tool rotating structure 105 at distal end 106 of elongated shaft 102 in a manner such that rotary movement of tool tip 160 relative to elongated shaft 102 is inhibited when tool tip 160 is mounted thereto. For example, the outer surface of proximal portion 164 may comprise a plurality of indentations, e.g., inverted indentations, that correspond with the plurality of indentations of tool rotating structure 105. Accordingly, as described above, actuation of actuator 104 at the proximal end of elongated shaft 102 causes rotation of elongated shaft 102, and accordingly tool tip 160 mounted thereto, relative to body portion 110.

In addition, each tool tip further may include base 162 sized and shaped to be releasably coupled to coupling element 134 of rod 130, e.g., inserted into the cavity defined by fingers 135 of rod 130, as described above. Base 162 may be rotationally symmetrical, e.g., symmetrical about a longitudinal axis of tool tip 160. For example, base 162 may comprise a mushroom shape, e.g., a bulbous portion extending from the proximal portion of the tool top via an elongated portion having an outer diameter that is less than the outer diameter of the bulbous portion. As described above, the cavity defined by fingers 135 of rod 135 may have a smaller width at its distal end compared with its middle and/or proximal portions, and may be open at the lateral sides of coupling element 134. Moreover, when tool activation mechanism 103 is in its fully retracted position, coupling element 134 of rod 130 may be positioned relative to magazine 170 such that the distal end of the cavity defined by fingers 135 is aligned with the elongated portion of base 162 and the bulbous portion of base 162 is aligned with the middle and/or proximal portions of the cavity. Accordingly, as magazine 170 rotates about its longitudinal axis to align the chamber holding the selected tool tip therein with track 101, and accordingly tool activation mechanism 103, the base of the non-selected tool tips disposed within the chambers of magazine 170 between track 101 and the chamber holding the selected tool tip may pass laterally through the cavity defined by fingers 135 until the base of the selected tool tip is disposed within the cavity, e.g., when the chamber holding the selected tool tip is aligned with tool activation mechanism 103. Further, when base 162 is disposed within the cavity of coupling element 134 and both base 162 and coupling element 134 are advanced through the lumen of elongated shaft 102, the inner wall of the lumen of elongated shaft 102 may be sized and shaped to prevent disengagement of base 162 from coupling element 134.

Accordingly, when base 162 is releasably coupled to coupling element 134 of rod 130, proximal coupling element 132 is releasably engaged with actuation end piece 118, and tool tip 160 is held in place via rack 120 and elongated shaft 102, actuation of rod 130, e.g., via actuator 114, in a first direction may cause rod 130 to move distally relative to rack 120 and apply a compressive force to base 162 to actuate tool tip 160 in a first degree of freedom, e.g., cause forceps tool tip 160a to open, and actuation of rod 130, e.g., via actuator 114, in a second direction opposite the first direction may cause rod 130 to move proximally relative to rack 120 and apply a tensile force to base 162 to actuate tool tip 160 in a second degree of freedom, e.g., cause forceps tool tip 160a to close, as described in further detail below with regard to FIGS. 11A and 11B. Accordingly, forceps tool tip 160a may be actuated to open/close without having to rely on a spring of the tool tip configured to facilitate opening of the forceps tool tip 160a. In some embodiments, coupling element 134 of rod 130 may be configured for providing a

rotational degree of freedom with respect to the mounted tool tip, e.g., a rotational degree of freedom of rod 130 and/or rack 120 with respect to mounted tool tip 160.

Referring now to FIGS. 9A to 9F, an exemplary magazine is provided. Magazine 170 may be a revolver-like drum with a plurality of chambers 176, each chamber 176 configured to house a different tool tip 160. For example, the tool tips may comprise at least one of a forceps tool having two jaws, a scissors tool, a probe, a dissector, a hook, a grasper, etc. Chambers 176 may be sized and shaped to slidably receive tool activation mechanism 103 therethrough. Moreover, each chamber 176 may comprise a geometry that permits tool tip 160 to be moved in and out of chamber 176 via distal end 174 of magazine 170, while prevent proximal movement of tool tip 160 proximally beyond proximal end 172 of magazine 170. For example, as shown in FIG. 9C, chambers 176 may each have a circular profile at distal end 174, sized and shaped to receive tool tip 160 therethrough, and as shown in FIG. 9D, chambers 176 may have a profile at proximal end 172 having a geometry that prevents passage of tool tip 160 therethrough. For example, the profile of chambers 176 at proximal end 172 may have flat sidewalls, such that tool tip 160 may not be moved proximally beyond proximal end 172 of magazine 170. In addition, at least a portion of the inner wall of chambers 176 may have a geometry that permits longitudinal movement of tool tip 160 therein, while preventing rotational movement of tool tip 160 therein relative to magazine 170. Accordingly, chambers 176 may be sized and shaped to facilitate handling of magazine 170 when magazine 170 is removed from body portion 110, e.g., for removing/replacing the tool tips disposed within the chambers of magazine 170.

As shown in FIGS. 9A to 9D, magazine 170 may comprise eight chambers 176, and slot 178, which is not configured to house a tool tip therein. Chambers 176 may be equally radially spaced from central axis 171 of magazine 171, such that magazine 170 may be selectively rotated about central axis 171, e.g., via actuation of the geared connection of drive gear 115 and driven gear 173 by motor 107b, to thereby align the angular position of a select chamber with track 101 of surgical device 100, as described above. As will be understood by a person having ordinary skill in the art, magazine 170 may have more or less than eight chambers 176, and/or more or less than one slot 178. Magazine 170 further may be configured to be movable along at least one translation axis. For example, magazine 170 may be configured to be movable along at least one translation axis along which chambers 176 of magazine 170 are arranged. In other words, chambers 176 of magazine 170 may be arranged along a line, allowing access to chambers 176 by sliding magazine 170. While magazine 170 is described herein as a revolver-like drum, in some embodiments, the magazine may have a different configuration that does not require rotation to align its chambers with track 101. For example, the chambers of the magazine may be arranged in a linear manner such that the magazine drive may be configured to cause the magazine to move translationally to align the chamber holding the selected tool tip with the track of the surgical device.

Referring now to FIGS. 10A to 10C, selection of an interchangeable tool tip is provided. In FIG. 10A, empty slot 178 of magazine 170 is aligned with track 101 of surgical device 100, and accordingly, with tool activation mechanism 103 in its retracted position, such that distal end 124 of rack 120 and distal coupling element 134 of rod 130 are positioned within track 101 proximal to slot 178. Upon selection of a desired tool tip, e.g., via display 14 and actuation of

actuator 113b and actuator 113c, the magazine drive may cause selective rotation of magazine 170 until the angular position of the select chamber 176 holding the desired tool tip, e.g., forceps tool tip 160a, is aligned with track 101, and accordingly, tool activation mechanism 103, as shown in FIG. 10B, and base 162 of forceps tool tip 160a enters the cavity defined by fingers 135 of coupling element 134, as described above. Upon alignment of select chamber 176 and track 101, and accordingly base 162 with coupling element 134 of rod 130, both rack 120 and rod 130 disposed therein may be advanced together distally, e.g., via actuation of the geared connection of geared surface 128 of rack 120 and pinion gear 111 by motor 107a of rack drive 121, from its retracted configuration towards its extended configuration to thereby advance forceps tool tip 160a distally out of distal end 174 of chamber 176 of magazine and through the lumen of elongated shaft 102 until forceps tool tip 160a is disposed at and mounted to distal end 106 of elongated shaft 102, as shown in FIG. 10C. For example, advancement of tool activation mechanism 103 distally along track 101 applies a compressive force to forceps tool tip 160a via the engagement of base 162 and coupling element 134 of rod 130.

Referring now to FIGS. 11A to 11D, actuation of tool activation mechanism 103 is provided. Actuation of tool activation mechanism 103 may be further elaborated by referring to FIGS. 12A to 12G, which illustrate the coupling mechanism between tool activation mechanism 103 and actuation bar end piece 118 of surgical device 100 during operation of the surgical device. FIGS. 11A and 11B illustrate the select tool tip 160, e.g., forceps tool tip 160a, mounted at distal end 106 of elongated shaft 102, with forceps tool tip 160a having jaws 166a, 166b in a closed state. Forceps tool tip 160a is a multi-part tool comprising a plurality of links, e.g., links 168, interconnected via a plurality of joints, between base 162 and jaws 166a, 166b, such that translational movement of base 162, e.g., via rod 130 while forceps tool tip 160a is coupled to distal end 106 of elongated shaft 102 and held in place via distal end 124 of rack 120 within elongated shaft 102, causes jaws 166a, 166b to transition between a closed state, as shown in FIG. 11A, and an open state, as shown in FIG. 11B. Accordingly, at least one tool part of the multi-part tool may be configured to be moved relative to another part of the multi-part tool, such as a remainder of the multi-part tool or a second moveable part of the multi-part tool. For example, the movable part of the multi-part tool may be, e.g., a cutting edge of a scissors tool or a jaw of a forceps tool, and the remainder or the second moveable part of the multi-part tool may be a corresponding edge or jaw of the multi-part tool. In some embodiments, the second moveable part of the multi-part tool also may be in a kinematic chain with the first moveable part, e.g., a lever that is connected to the first moveable part.

As shown in FIGS. 11A and 11B, actuator 114, e.g., an operating lever, may be operatively coupled to actuation bar end piece 118 via joint-connected actuation bar 119, e.g., an articulated connection. For example, actuator 114 may be spring loaded and biased towards the configuration shown in FIG. 11B. FIG. 12A illustrates body portion 110, particularly the coupling mechanism between the proximal end of tool activation mechanism 103, e.g., proximal end 122 of rack 120 and proximal coupling element 132 of rod 130, and actuation bar end piece 118 when forceps tool tip 160a is in the closed state shown in FIG. 11A, and FIG. 12B illustrates body portion 110, particularly the coupling mechanism between the proximal end of tool activation mechanism 103 and actuation bar end piece 118 when forceps tool tip 160a

is in the open state shown in FIG. 11B. As shown FIGS. 12A and 12B, when forceps tool tip 160a mounted to distal end 106 of elongated shaft 102, such that tool activation mechanism 103 is in its fully extended configuration, actuation bar end piece 118 is in an engaged state, e.g., pivoted upward, where actuation bar end piece 118 is releasably engaged with proximal coupling element 132 of rod 130. For example, actuation bar end piece 118 may comprise a hook shape, e.g., comprising a wedge, that engages with proximal coupling element 132. For example, the hook shape of actuation bar end piece 118 may comprise a recess having a geometry configured to releasably lock with proximal coupling element 132. Accordingly, body portion 110 may comprise an internal cavity sized and shaped to hold actuation bar end piece 118 therein, and further to permit rotational and translational movement of actuation bar end piece 118 therein.

Accordingly, upon actuation of actuator 114 in a first direction, as shown in FIGS. 11A and 12A, actuation bar 119 causes actuation bar end piece 118 to move proximally relative to body portion 110 and apply a tensile force to rod 130 via the engagement of proximal coupling element 132 and actuation bar end piece 118, to thereby move rod 130, and accordingly base 162 of forceps tool tip 160a, proximally relative to rack 120 and elongated shaft 102. Proximal movement of base 162 of forceps tool tip 160a causes jaws 166a, 166b of forceps tool tip 160a to transition towards the closed state via links 168, as shown in FIG. 11A. Moreover, upon actuation of actuator 114 in a second direction, as shown in FIGS. 11B and 12B, actuation bar 119 causes actuation bar end piece 118 to move distally relative to body portion 110 and apply a compressive force to rod 130 via the engagement of proximal coupling element 132 and actuation bar end piece 118, to thereby move rod 130, and accordingly base 162 of forceps tool tip 160a, distally relative to rack 120 and elongated shaft 102. Distal movement of base 162 of forceps tool tip 160a causes jaws 166a, 166b of forceps tool tip 160a to transition towards the open state via links 168, as shown in FIG. 11B. Actuator 114 may not move rod 130 when no tool tip 160 is mounted to distal end 106 of elongated shaft 102, e.g., when proximal coupling element 132 of rod 130 and actuating bar end piece 118 are disengaged.

Upon selection of another interchangeable tool tip for mounting at distal end 106 of elongated shaft 102, tool activation mechanism 103 transitions from its extended configuration towards its retracted configuration, thereby pulling the current select tool tip 160, e.g., forceps tool tip 160a, proximally through the lumen of elongated shaft 102, as shown in FIG. 11C, until forceps tool tip 160a is returned to its corresponding chamber 176 of magazine 170, e.g., in a magazine configuration, and tool activation mechanism 103 is in its fully retracted position, as shown in FIG. 11D. As shown in FIG. 11D, in the fully retracted configuration, at least the proximal portion of tool activation mechanism 103 may bend about a bend axis, e.g., a center of receptacle 108, such that tool activation mechanism 103 is disposed within receptacle 108 in a rolled configuration. Accordingly, by disposing tool activation mechanism 103 in a rolled configuration within receptacle 108 of surgical device 100 in its fully retracted configuration, surgical device 100 provides a more compact device than currently available surgical devices. As described above, upon selection of a different tool tip, e.g., via display 14 and actuation of actuator 113b and actuator 113c, rack drive 121 causes translational movement of tool activation mechanism 103,

e.g., via the geared connection between geared surface 128 of rack 120 and pinion gear 111, proximally along track 101 of surgical device 100.

FIG. 12C illustrates the proximal end of tool activation mechanism 103 as tool activation mechanism 103 begins transitioning from its fully extended configuration towards its retracted configuration. For example, proximal end 122 of rack 120 may comprise a wedge shaped profile that engages with a corresponding geometry of actuation bar end piece 118 upon proximal movement of rack 120 relative to actuation bar end piece 118, which causes actuation bar end piece 118 to pivot from the engaged state to a disengaged state, as shown in FIG. 12C. As shown in FIG. 12C, in the disengaged state, actuation bar end piece 118 is disengaged from proximal coupling element 132, such that rod 130 is permitted to move proximally along with rack 120 relative to actuation bar end piece 118 and body portion 110, as shown in FIG. 12D.

FIG. 12E illustrates body portion 110 when tool activation mechanism 103 is in its fully retracted position, such that the distal end of tool activation mechanism 103, e.g., distal end 124 of rack 120 and distal coupling element 134 of rod 130, is disposed proximal to magazine 170, and accordingly, the chamber of magazine 170 aligned with track 101 of surgical device 100. As described above, proximal end 172 of chamber 176 of magazine 170 may be configured to prevent proximal movement of tool tip 160 proximally beyond proximal end 172 of chamber 176. Accordingly, as tool activation mechanism 103 is moved to its fully retracted configuration and tool tip 160 is returned to its corresponding chamber 176, base 162 of tool tip 160 may be disengaged from coupling element 134 of rod 130 upon rotation of magazine 170, e.g., to thereby receive the base of another selected tool tip within the cavity of coupling element 134.

As described above, the magazine drive of surgical device 100 may then cause rotation of magazine 170, e.g., via the geared connection between drive gear 115 and driven gear 173, to align the angular position of the chamber holding the newly selected tool tip with track 101 of surgical device 100. Drive rack 121 of surgical device 100 may then cause translation of tool activation mechanism 103 distally relative to body portion 110 to transition from its retracted configuration towards its extended configuration, and engage and advance the select tool tip 160 from the magazine configuration within chamber 176 of magazine 170 towards distal end 106 of elongated shaft 102, as described above with regard to FIGS. 10B and 10C. As shown in FIG. 12F, when tool activation mechanism 103 is advanced distally such that proximal end 122 of rack 120 is disposed distal to actuation bar end piece 118, actuation bar end piece 118 may transition from its disengaged state towards its engaged state. For example, actuation bar end piece 118 may be spring loaded and biased towards its engaged state. As shown in FIG. 12F, proximal coupling element 132 of rod 130 is still disposed proximally to actuation bar end piece 118. As shown in FIG. 12G, further distal advancement of rack 120 and rod 130 relative to actuation bar end piece 118 causes proximal coupling element 132 to apply a force to actuation bar end piece 118, which causes actuation bar end piece 118 to pivot slightly downward to permit proximal coupling element 132 to move distally relative to actuation bar end piece 118, as shown in FIG. 12G. As described above, when tool activation mechanism 103 is in its fully extended configuration, actuation bar end piece 118 is engaged with proximal coupling element 132 of rod 130 in its engaged state, as shown in FIG. 12B, and tool tip 160 is in its mounted configuration at distal end 106 of elongated shaft 102.

Referring now to FIG. 13, the distal region of an alternative exemplary surgical device having a tool tip configured for electric cauterization mounted thereto is provided. Distal region 106' of elongated shaft 102' may be constructed similar to distal region 106 of elongated shaft 102, except that elongated shaft 102' may be configured to transmit electrical energy to forceps tool tip 160a', which may be constructed similar to forceps tool tip 160a described above. For example, forceps tool tip 160a' may be a multi-part tool having links 168' interconnected via a plurality of joints between base 162' and jaws 166a', 166b'. The surgical device may be configured to provide two pole lines for transmitting power to different parts of forceps tool tip 160a', e.g., jaws 166a' and 166b'. For example, elongated shaft 102' may be configured to transmit electric power to forceps tool tip 160a', thereby forming a first pole line. In addition, rod 130 may further be configured to transmit electric power to jaws 166a', 166b' of forceps tool tip 160a', thereby forming a second pole line. In another example, elongated shaft 102' may also be configured to transmit electric power to forceps tool tip 160a' via two integrated pole lines, thereby forming both a first and second pole line. Accordingly, the surgical device may be connected to a power generator configured to provide electrosurgical power to the surgical device, and accordingly, the tool tip mounted thereto for monopolar and/or bipolar electric cauterization.

In FIG. 13, electrically insulating layers 180 of forceps tool tip 160a' and elongated shaft 102' are indicated by bold lines. Accordingly, as shown in FIG. 13, elongated shaft 102' may comprise an outer electrically insulating layer 180, and parts of forceps tool tip 160a' may be insulated from each other via inner electrically insulating layer 180, e.g., when forceps tool tip 160a' is configured for bipolar electric cauterization. In some embodiments, the select tool tip may be configured for monopolar cauterization, such that inner electrically insulating layers for electrically insulating parts of the tool tip may not be necessary.

Moreover, the body portion of the surgical device may comprise a bore configured for receiving the proximal portion of elongated shaft 102' therein, which may form a sleeve bearing. The bore may be made from a conductive material, such as stainless steel, and may be configured for transmitting electric power from the body portion to elongated shaft 102', e.g., the first pole line. In addition, power may be transmitted to rod 130 via the actuation bar end piece of the body portion, e.g., the second pole line. For example, the surgical device may comprise an electrical contact between the actuation bar end piece and the proximal coupling element of rod 130 when the actuation bar end piece engages the proximal coupling element of rod 130, as described above. Further, the surgical device may comprise at least one of a flexible cable, a joint, or a sliding contact for providing an electrical connection of a power line from the body portion and the actuation bar end piece.

Additionally, or alternatively, power may also be transmitted to rod 130 via a section of rack 120. For example, a section of rack 120 disposed within the body portion of the surgical device when the tool tip is mounted to distal region 106' of elongated shaft 102' may be conductive. Accordingly, rack 120 may optionally connect an electrical contact inside the body portion with rod 130. A remainder of rack 120 may comprise at least one insulating layer, such as a toothed layer made from an insulating polymer, to thereby advantageously electrically insulate rod 130 from elongated shaft 102'. In some embodiments, a distal portion of rack 120 and/or sliding member 136 may also be formed from an electrically insulating material. Accordingly, the surgical

device may comprise at least two cables insulated from one another, e.g., for providing the two pole lines. For example, when a tool tip for bipolar cauterization is mounted to distal region 106' of elongated shaft 102', the two pole lines may be electrically connected to the output of a power generator, e.g., via a switching module.

If a tool tip for monopolar cauterization is mounted to distal region 106' of elongated shaft 102', the switching module may disconnect the unused pole line and may connect the other pole line to the monopolar output of the power generator. As will be understood by a person having ordinary skill in the art, permutations of the two cables for providing two pole lines, with the consequent permutations of the two voltages, or vice versa, may be encompassed by the other surgical devices described herein. In some embodiments, the surgical device further may comprise a third pole line for transmitting electric power to the tool for electric cauterization, as described in further detail below. For example, the third pole line may be configured to be attached to, and electrically insulated from, elongated shaft 102'. Accordingly, the surgical device may comprise at least three cables insulated from one another, e.g., for providing the three pole lines.

Referring now to FIG. 14, the distal region of the elongated shaft of an alternative exemplary surgical device is provided. As shown in FIG. 14, the surgical device may comprise three cables (e.g., cables 191, 192, 193) insulated from each other for transmitting electric power to the interchangeable tool tip mounted at distal portion 190 of elongated shaft 102" of the surgical device, e.g., at the distal end of elongated shaft 102" as described above, particularly to an interchangeable tool tip configured for electric cauterization. First cable 191, second cable 192, and third cable 193 may be comprised in elongated shaft 102". The voltages of the three cables may be different, e.g., V_1 for first cable 191, V_2 for second cable 192, V_3 for third cable 193. First cable 191 may contact elongated shaft 102" and/or define a first region D_1 of distal portion 190 of elongated shaft 102", such that first region D_1 comprises voltage V_1 . Second cable 192 may contact a second region D_2 of distal portion 190, such that second region D_2 comprises voltage V_2 . Third cable 193 may contact a third region D_3 of distal portion 190, such that third region D_3 comprises voltage V_3 . Regions D_1 , D_2 , and D_3 may be electrically insulated from each other via insulating components 194. As will be understood by a person having ordinary skill in the art, permutations of the three cables, with the consequent permutations of the three voltages, or vice versa, may be encompassed by the other surgical devices described herein.

Referring now to FIGS. 15A and 15B, an exemplary interchangeable tool tip configured for tripolar electric cauterization is provided. As shown in FIG. 15A, tool tip 160c may comprise a tool end portion 195. Tool tip 160c further may comprise first tool region T_2 and second tool region T_3 , which may be electrically insulated from each other, and electrically insulated from tool end portion 195, via insulating elements 200. As will be understood by a person having ordinary skill in the art, tool regions T_2 and/or T_3 and/or tool end portion 195 may be encompassed by the other tool tips described herein. Tool tip 160c further may comprise first part 196, second part 197, and third part 198, which may be electrically insulated from each other. At least one of first part 196, second part 197, or third part 198 may be movable. For example, third part 198 may be movable.

In addition, tool tip 160c may be configured to have a distinct electrical connection to any of the cables (e.g., cables 191, 192, 193) of the surgical device. For example,

the electrical connections may include electrical connections to first part 196, second part 197, and third part 198, e.g., tool tip 160c may comprise electrical connection 201 between first part 196 and tool end portion 195, electrical connection 202 between second part 197 and first tool region T₂, and electrical connection 203 between third part 198 and second tool region T₃, as shown in FIG. 15B. As will be understood by a person having ordinary skill in the art, permutations of connections 201, 202, and 203 may be encompassed by the other tool tips described herein. As shown in FIG. 15B, when tool tip 160c is mounted to distal portion 190 of elongated shaft 102", for example, via the tool activation mechanism, tool end portion 195 may generally contact first region D₁ of distal portion 190, thus establishing an electrical connection between first part 196 and first cable 191. First part 196 may therefore act as a first electrode. Further, first tool region T₂ may contact second region D₂ of distal portion 190, thus establishing an electrical connection between second part 197 and second cable 192. Second part 197 may therefore act as a second electrode. Further, second tool region T₃ may contact third region D₃ of distal portion 190, thus establishing an electrical connection between third part 198 and third cable 193. Third part 198 may therefore act as a third electrode.

Referring now to FIG. 16, the proximal portion of an alternative exemplary interchangeable tool tip configured for tripolar electric cauterization is provided. Tool tip 160d may be constructed similar to tool tip 160c. For example, tool end portion 195' of tool tip 160d corresponds with tool end portion 195 of tool tip 160c. When the tool tip 160d is mounted to the distal portion of the elongated shaft of the surgical device (not shown), tool end portion 195' may comprise first voltage V₁, first tool region T₂ may comprise a second voltage V₂, and second tool region T₃ may comprise third voltage V₃, as shown in FIG. 16.

Referring now to FIG. 17, an exemplary surgical device is shown connected to a power generator via an exemplary switching module. Generator 210 may be configured to provide electrical power to surgical device 100, particularly to tool tip 160, e.g., an interchangeable tool tip configured for monopolar, bipolar, and/or tripolar cauterization, mounted on the distal portion of the elongated shaft of surgical device 100. Switching module 211 may be configured to manage the electrical connections between generator 210 and surgical device 100, as described above. For example, the connection to surgical device 100 may be achieved with one, two, or three cables (e.g., cables 212, 213, 214). For example, cables 212, 213, 214 may be electrically connected to cables 191, 192, 193, as described above with regard to FIG. 14, respectively. As will be understood by a person having ordinary skill in the art, permutations of the cables and/or their connections may be encompassed by the other surgical devices described herein. More generally, it will be understood that the specific connections of cables 212, 213, 214 are shown as a preferred embodiment in FIG. 17 for illustrative purpose only and this should by no means be construed to limit the scope of the present invention. For example, the ordinarily skilled person will understand that embodiments of the present invention may encompass a number of cables and/or their connections different than the number of cables and/or their connections shown in FIG. 17.

The utilization of surgical device 100 connected to generator 210, via switching module 211, wherein surgical device 100 may comprise three cables, e.g., three pole lines, and wherein switching module 211 may be adapted for a tripolar setup, may have significant advantages. For

example, with this setup, no safety critical switching of connections to the generator may be necessary. Further, as another example, no switching off of connections to the generator may be necessary, other than, for example, when the system's motors run. Moreover, if an interchangeable tool tip is locked in a wrong chamber of the magazine, no further safety risk may be introduced. Additionally, there may be no need for further identification of monopolar tool tips. As will be understood by a person having ordinary skill in the art, if an interchangeable tool tip with three electrodes is used, e.g., where the three electrodes are represented by three parts of the tool tip as described above, then a first couple of electrodes out of the three electrodes may be used to perform, e.g., sealing of tissue, and a second couple of electrodes out of the three electrodes may be used to perform, e.g., cutting of tissues.

Referring now to FIG. 18, electrode assignment options for exemplary interchangeable tool tips are provided. The tool tips (e.g., tool tips 160e-160m) may be adapted, for example, for monopolar, bipolar, and/or tripolar cauterization. The distal portions (e.g., distal portion 190', 190", 190'''') of the corresponding elongated shafts of the corresponding surgical devices may comprise three cables, as described above with regard to FIG. 14. As explained above, regions D₁, D₂, and D₃ of the each of the distal portions of the elongated shafts may be at different voltages. For example, in a first configuration 215, regions D₁, D₂, and D₃ of distal portion 190' may comprise voltages V₂, V₃, and V₁, respectively. Moreover, in a second configuration 216, regions D₁, D₂, and D₃ of distal portion 190" may comprise voltages V₃, V₂, and V₁, respectively. In a third configuration 217, regions D₁, D₂, and D₃ of distal portion 190''' may comprise voltages V₃, V₁, and V₂, respectively.

The interchangeable tool tips (e.g., tool tips 160e-160m), particularly parts of the tool tips such as terminal parts of the tool tips, some of which may be movable, may be configured to have a distinct electrical connection to at least some of the three cables comprised in the surgical device, e.g., via electrical connections to regions D₁, D₂, and D₃. For example, an electrical connection of the terminal parts of the tool tips to region T₂, region T₃, and/or the tool end portion may be achieved with cables. The further electrical connection between regions T₂ and/or T₃, and regions D₂ and/or D₃ may be achieved with, e.g., spring contacts. The further electrical connection between the tool end portion and region D₁ may generally be present in most cases when the tool tip is mounted to the distal portion of the respective elongated shaft, unless insulating elements are used to prevent this. As described above, the terminal parts of the tool tips may act as electrodes. Insulation elements also may be utilized to electrically insulate the electrodes from each other and/or to electrically insulate the terminal parts of the tool tips from at least some of the three cables. The combination of the distinct electrical connection to at least some of the three cables and of the use of insulation elements may allow, e.g., (1) an interchangeable tool tip to be a monopolar hook 160e, a bipolar grasper 160f, and/or a tripolar grasper 160g in the first configuration 215, (2) an interchangeable tool tip to be a monopolar hook 160h, a bipolar grasper 160i, and/or a tripolar grasper 160j in the second configuration 216, and/or (3) an interchangeable tool tip to be a monopolar hook 160k, a bipolar grasper 160l, and/or a tripolar grasper 160m in the third configuration 217.

Referring now to FIG. 19, additional exemplary interchangeable tool tips are provided. As shown in FIG. 19, the tool tips may be related to the first configuration 215, the second configuration 216, and/or the third configuration 217

as described above with regard to FIG. 18. For example, bipolar grasper 160^f may be achieved in the second configuration 216 by a distinct connection to three cables comprised in the surgical device. For example, an electrical connection 219 may be present between second part 198' and second region T₃ of bipolar grasper 160^f, and an electrical connection 220 may be present between first part 196' and first region T₂ of bipolar grasper 160^f. One or more of said parts may be movable, for example, second part 198' may be movable. Further, bipolar grasper 160^f is mounted to the distal portion of the elongated shaft of the surgical device, an electrical connection between second region T₃ and region D₃ may be present, and an electrical connection between first region T₂ and region D₂ may be present, wherein said connections may be achieved via spring contacts 218. Further, region T₃, region T₂, and tool end portion 195 may be electrically insulated via insulating elements 221.

Each of the exemplary interchangeable tool tips of FIG. 19 (e.g., tool tips 160^e, 160^f, 160^h, 160ⁱ, 160^k, 160^l, and 160ⁿ-160^p) may exhibit distinct connection to three cables comprised in the surgical device. Generally, electrical connection between regions of the tool tips, e.g., regions T₂, T₃, and regions of the distal portion of the elongated shaft, e.g., regions D₂, D₃, may further be achieved via spring contact rings 218 when the tool tip is mounted to the distal portion of the elongated shaft. As would be understood by a person having ordinary skill in the art, an electrical connection between tool end portion 195 of the respective tool tip and region D₁ may generally be present in most cases when the tool tip is mounted to the distal portion of the elongated shaft, unless insulating elements are used to prevent this. For example, in the case of the bipolar grasper 160^f, insulation elements may be present so that no electrical connection between tool end portion 195 and region D₁ is present. Further, insulating elements 221 may be comprised in the distinct electrical connection.

For example, the tool tips may have insulating elements that may electrically insulate the operative portion of the tool tip, e.g., the moving parts of the tool tip, from one (bipolar), two (monopolar), or all three (no electrosurgical function) of the three cables that may be comprised in the surgical device. As described herein, the cables may be referred to as pole lines, and the operative portion of the tool tips, e.g., the moving parts of the tool tip, may be referred to as electrodes. Various electrode configurations may be possible, which would result in different insulation geometries at the tool tips. This may be illustrated, for example, by a bipolar grasper and/or a monopolar hook and/or a monopolar grasper. Moreover, if the tool tip is a hook, the tool tip may comprise an internal electrical connection between the terminal part of the hook and tool end portion.

As would be understood by a person having ordinary skill in the art, the distinct electrical connections, as exemplified in FIG. 19, but not described in detail for the sake of brevity, may allow for a variety of interchangeable tool tips. Accordingly, the ordinarily skilled person will understand how such distinct electrical connections may be achieved based on, for example, FIG. 19. A detailed description is given above in the case of the bipolar grasper 160^f in the first configuration 215. Similarly, a bipolar grasper 160ⁱ may be achieved in the second configuration 216, and a bipolar grasper 160^f may be achieved in the third configuration 217. As shown in FIG. 19, monopolar hooks 160^e, 160^h, and 160^k may be achieved in the first, second, and third configurations 215, 216, 217, respectively. Further, monopolar graspers 160ⁿ, 160°, and

160^p may be achieved in the first, second, and third configurations 215, 216, 217, respectively.

While various illustrative embodiments of the invention are described above, it will be apparent to one skilled in the art that various changes and modifications may be made therein without departing from the invention. The appended claims are intended to cover all such changes and modifications that fall within the true scope of the invention.

What is claimed:

1. A surgical device comprising:

a body portion;

an elongated shaft having a proximal end coupled to the body portion, a distal end, and a lumen extending therebetween;

a magazine coupled to the body portion and comprising a plurality of chambers, each chamber configured to receive an interchangeable tool tip therein, the magazine configured to be selectively actuated to align a selected chamber of the plurality of chambers with the proximal end of the elongated shaft;

one or more motors operatively coupled to the magazine, the one or more motors configured to be actuated to move the magazine relative to the body portion;

a tool activation mechanism comprising a distal region configured to be releasably coupled to the interchangeable tool tip of the selected chamber, the tool activation mechanism configured to transition between a retracted configuration within the body portion where the distal region is disposed proximal to the selected chamber, and an extended configuration where the distal region is coupled to the interchangeable tool tip of the selected chamber and extends through the lumen of the elongated shaft such that the interchangeable tool tip is mounted at the distal end of the elongated shaft; and a user interface operatively coupled to the one or more motors, the user interface configured to receive user input indicative of the selected chamber,

wherein the one or more motors are configured to actuate the magazine to align the selected chamber with the proximal end of the elongated shaft based on the user input.

2. The surgical device of claim 1, wherein the tool activation mechanism is substantially rigid against compression and elongation and flexible against bending as the tool activation mechanism transitions from the extended configuration to the retracted configuration.

3. The surgical device of claim 2, wherein the tool activation mechanism comprises a rack, and an actuation rod disposed within a lumen of the rack, and wherein the rack and the actuation rod are configured to move together as the tool activation mechanism transitions between the retracted configuration and the extended configuration.

4. The surgical device of claim 3, wherein the rack comprises a plurality of joint-connected rack elements.

5. The surgical device of claim 3, wherein the rack is configured to substantially bend about a single bend axis.

6. The surgical device of claim 3, wherein a distal end of the rack is configured to releasably engage a proximal portion of the interchangeable tool tip, and wherein a distal end of the actuation rod comprises a coupling element configured to be releasably coupled to an engagement portion of the interchangeable tool tip.

7. The surgical device of claim 6, wherein, when the coupling element is coupled to the engagement portion, the actuation rod is configured to be actuated to move axially relative to the rack to thereby actuate the interchangeable tool tip.

8. The surgical device of claim 7, wherein the interchangeable tool tip comprises a tool configured to be actuated in an open and close degree of freedom, and wherein actuation of the actuation rod actuates the interchangeable tool tip in the open and close degree of freedom.

9. The surgical device of claim 7, wherein the body portion comprises an actuation bar configured to be releasably coupled to a proximal coupling element of the actuation rod in the extended configuration, the actuation bar configured to be actuated to move the actuation rod axially relative to the rack.

10. The surgical device of claim 9, wherein the body portion is sized and shaped to be held in a user's palm, and wherein the body portion comprises an interface operatively coupled to the actuation bar, the interface configured to be actuated by the user to actuate the actuation bar and move the actuation rod axially relative to the rack.

11. The surgical device of claim 3, wherein the rack comprises a geared outer surface, and wherein the body portion further comprises a worm gear operatively coupled to a pinion gear operatively coupled to the geared outer surface, the worm gear configured to be actuated to cause rotation of the pinion gear to thereby cause translational movement of the rack via a geared connection between the pinion gear and the geared outer surface.

12. The surgical device of claim 1, wherein each chamber of the plurality of chambers of the magazine is sized and shaped to prevent proximal movement of the interchangeable tool tip beyond a proximal end of the chamber.

13. The surgical device of claim 1, wherein one or more chambers of the plurality of chambers of the magazine comprise a geometry configured to receive the interchangeable tool tip in a predetermined aligned manner.

14. The surgical device of claim 13, wherein the geometry is configured to prevent rotation of the interchangeable tool tip relative to the chamber.

15. The surgical device of claim 1, wherein the body portion comprises a receptacle sized and shaped to slidably receive the tool activation mechanism in the retracted configuration.

16. The surgical device of claim 15, wherein the receptacle is configured to permit the tool activation mechanism to substantially bend about a bend axis as the tool activation mechanism transitions from the extended configuration to the retracted configuration, the bend axis substantially orthogonal to a longitudinal axis of the elongated shaft.

17. The surgical device of claim 1, wherein the elongated shaft is configured to transmit electric power from a generator to the interchangeable tool tip mounted at the distal end of the elongated shaft.

18. The surgical device of claim 17, wherein the interchangeable tool tip comprises a tool configured for electric cauterization.

19. The surgical device of claim 1, further comprising: an actuator configured to rotate the elongated shaft and 55 the interchangeable tool tip mounted thereon relative to the body portion, wherein the distal end of the elongated shaft is configured to prevent rotation of the interchangeable tool tip relative to the elongated shaft.

20. The surgical device of claim 19, wherein the actuator comprises a rotatable knob disposed on the body portion.

21. The surgical device of claim 1, further comprising a handle at the proximal end of the elongated shaft, the handle configured to be held by the user for performing surgery.

22. The surgical device of claim 1, wherein the surgical device is configured for use with a surgical robot system.

23. The surgical device of claim 1, wherein the user interface comprises a display that displays various types of interchangeable tool tips within the plurality of chambers, and

5 wherein a user is permitted to select a type of interchangeable tool tip using the display.

24. The surgical device of claim 1, wherein the interchangeable tool tips within the plurality of chambers comprise at least one of a hook, a grasper, or scissors.

10 25. The surgical device of claim 1, wherein the magazine is rotatably coupled to the body portion, and wherein the plurality of chambers are equally radially disposed about a longitudinal axis of the magazine.

15 26. A surgical device comprising:
a body portion comprising a worm gear;

an elongated shaft having a proximal end coupled to the body portion, a distal end, and a lumen extending therebetween;

a magazine coupled to the body portion and comprising a plurality of chambers, each chamber configured to receive an interchangeable tool tip therein, the magazine configured to be selectively actuated to align a selected chamber of the plurality of chambers with the proximal end of the elongated shaft; and

20 a tool activation mechanism comprising a rack and an actuation rod disposed within a lumen of the rack, the rack comprising a geared outer surface operatively coupled to a pinion gear operatively coupled to the worm gear, the worm gear configured to be actuated to cause rotation of the pinion gear to thereby cause translational movement of the rack via a geared connection between the pinion gear and the geared outer surface,

25 wherein the tool activation mechanism is configured to transition between a retracted configuration within the body portion where a distal region of the tool activation mechanism is disposed proximal to the selected chamber, and an extended configuration where the distal region is releasably coupled to the interchangeable tool tip of the selected chamber and extends through the lumen of the elongated shaft such that the interchangeable tool tip is mounted at the distal end of the elongated shaft, and

30 wherein the rack and the actuation rod are configured to move together as the tool activation mechanism transitions between the retracted configuration and the extended configuration.

27. The surgical device of claim 26, further comprising: one or more motors operatively coupled to the magazine, the one or more motors configured to be actuated to move the magazine relative to the body portion; and a user interface operatively coupled to the one or more motors, the user interface configured to receive user input indicative of the selected chamber,

35 wherein the one or more motors are configured to actuate the magazine to align the selected chamber with the proximal end of the elongated shaft based on the user input.

28. The surgical device of claim 26, wherein a distal end of the rack is configured to releasably engage a proximal portion of the interchangeable tool tip,

40 wherein a distal end of the actuation rod comprises a coupling element configured to be releasably coupled to an engagement portion of the interchangeable tool tip, and

wherein, when the coupling element is coupled to the engagement portion, the actuation rod is configured to be actuated to move axially relative to the rack to thereby actuate the interchangeable tool tip.

29. The surgical device of claim **26**, wherein the tool activation mechanism is substantially rigid against compression and elongation and flexible against bending as the tool activation mechanism transitions from the extended configuration to the retracted configuration. 5

30. The surgical device of claim **26**, wherein the body portion comprises a receptacle sized and shaped to slidably receive the tool activation mechanism in the retracted configuration. 10
